UNITED STATES PATENT OFFICE.

JOHN B. BARTHOLOMEW, OF PEORIA, ILLINOIS.

PNEUMATIC STACKER.

SPECIFICATION forming part of Letters Patent No. 633,561, dated September 26, 1899.

Application filed December 30, 1897. Renewed November 18, 1898. Serial No. 696,827. (No model.)

To all whom it may concern:

Be it known that I, JOHN B. BARTHOLOMEW, a citizen of the United States, residing at Peoria, in the county of Peoria and State of Illinois, have invented certain new and useful Improvements in Pneumatic Stackers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 Figure 1 is a side elevation of a pneumatic stacking mechanism embodying my improvements. Fig. 2 is a top plan view of the same. Fig. 3 is a detail view. Fig. 4 is a side elevation showing a slightly-modified construction. Fig. 5 is a top plan view of the parts shown in Fig. 4. Fig. 6 is a side elevation of the stacker trunk or duct, constructed as shown in Fig. 1, on an enlarged scale. Fig. 7 is a transverse sectional view taken through 25 the duct on the line 7-7 of Fig. 1 and showing the support for the stacker-tube in rear elevation.

In the drawings, A designates the rear end of a threshing-machine, which may be of several styles.

A' designates a vertical tube or duct by which straw and chaff from the interior of the thresher are conducted upwardly to the discharge trunk or duct. The latter consists, in 35 the embodiment of my invention herein illustrated, of a single curved section B, a second section B', telescopically connected to the section B, and an outer section B², telescopically mounted upon the second section B' and provided at its outer end with a deflecting hood or shield for guiding the straw escaping from the outlet at the end of said section B². As the present improvements relate more particularly to mechanism for automatically adjusting this hood or straw-deflector with relation to the body of the trunk, I do not believe it necessary to either illustrate or describe in detail the construction or manner of mounting and supporting the trunk. It is 45 sufficient to say that C indicates a peripherally-toothed ring or base, upon which the stacker-tube is mounted, and c designates a

pinion for rotating said ring and tube about a vertical axis. Suitable mechanism is provided for automatically reversing the direction of revolution of the pinion c at predetermined intervals, so that the stacker-tube will be vibrated through the arc of the circle concentric with the axis of the ring C, and at T I have indicated one form of mechanism for 55 elongating the discharge-trunk to correspond to the increase in the height of the stack.

With machines heretofore devised for utilizing a blast of air for stacking straw means have been provided for depositing the straw 65 at various points in a line extending transversely of the stack, (being the line of movement of the outer end of the discharge trunk or tube); but the result has been that the straw was deposited in a relatively narrow ridge-like form, and it was necessary to manually distribute the straw to points beyond such ridge to provide a proper stack.

The object of the present invention is to provide means by which the straw will be 75 automatically discharged uniformly over the entire top of the stack.

As shown in the drawings, the hood or deflector at the outer end of the stacker-trunk consists of three telescoping sections D D' D². 80 The inner of these sections D is rigidly secured to the tube-section B², while the other two sections D' D² are pivotally connected together and to said inner section at d. Short sections of chain or cable d' are provided for limiting the outward or downward movement of the sections D' D² relatively to each other and to the section D. When the lower or outer section D² of the deflector is in the position indicated in full lines in Fig. 1, 85 for example, it will be seen that such section acts to limit the outward motion of the straw and to cause the same to be deposited at points between the inner end of the cut-away portion b² of the outer tube-section and said 90 deflector-section, and it will also be seen that if the said outer deflecting-section D² should be rocked about its pivot d at any instant the straw would be carried to points relatively farther from the body of the stacker-tube. To effect this automatic vertical movement of the deflector, I provide the following 95 devices:

Referring to that embodiment of my inven-

tion illustrated in Figs. 1, 2, and 6, E designates a lever-arm which is riveted or otherwise rigidly secured to one of the side walls of the deflector-section D² and extends on opposite sides of the fulcrum or pivot d. At its upper end this lever-arm carries a guide roller or sheave e, about which extends a rope or cable F. This rope or cable F extends around suitable guide rollers or sheaves G G', mounted, respectively, on the section B² of the stacker-trunk and on the arm or standard h, extending upwardly from the bracing and supporting arm H, and has one end connected to one arm of a bell-crank lever K and its other end connected to a hook-like projection on the inclined brace-arm H'. The bell-crank lever K is fulcrumed at k upon a bracket secured to one of the framing-bars L of the trunk, and the arm k' of said lever is connected by a link 20 or rod M with a sprocket N. The latter, which is mounted on a suitable shaft journaled in the stacker-trunk-supporting frame, is connected by a sprocket-chain N' with another sprocket N². The latter is mounted 25 upon a horizontal shaft n, provided also with a bevel-pinion n', which meshes with a bevel-gear n², carried by a vertical shaft n³. This shaft n³ is provided at its lower end with a pinion n⁴, which meshes with the teeth of a 30 segmental rack N³, rigidly and stationarily secured in position upon the framework on the thresher A and extending concentric with the ring or base C, by which the stacker-trunk is 35 horizontally vibrated.

From the above description it will be seen that as the ring or base C is revolved the pinion n⁴ will be carried around the rack N³, and the engagement between the teeth of said pinion and rack will rotate the sprockets N² 40 and rock the lever K about its fulcrum k. As the lower end of the rope or cable F is fixed and held stationary, it is seen that as the upper end of the lever K moves rearwardly in the direction indicated by the arrow the deflector-section D² will be rocked upwardly and rearwardly about its pivot at d. A coiled spring D⁴ is interposed between the rear end of the lever-arm E and a lug b³ 45 on the stacker-tube, and this spring acts to return the deflector-section D² to its original position as the rotation of the sprocket N causes the upper end of the lever K to move forward. The lower end of the cord or cable F is preferably provided with a ring f, adapted 50 to engage with either of the series of hook-like projections h' on the brace-arm H', and this lower end of such cable is within easy reach of an operator standing on the ground adjacent to the rear end of the machine A.

By drawing the rope or cable F the operator 55 may vary the initial position of the deflector-section D² with relation to the stacker-tube and secure the same in such position by attaching the ring f to the proper hook h'.

By connecting the automatically-acting power devices, which actuate the deflector relatively to the duct, to the deflector by

means of a cord or chain arranged substantially as set forth—that is to say, a cord or equivalent which is secured at one point to the automatic deflector-moving devices and secured at another point to a relatively stationary holder or support, as to the parts at h—I provide for automatically moving the deflector relatively to the duct by the power devices and also provide for moving it by hand independently of the power devices. The operator, should he at any time see the stack taking an undesirable shape, can by hand open the deflector by drawing upon the cord, even though the automatically-acting mechanism is at work.

It is usual to provide stacker mechanisms of this class with means for unclutching or throwing out of action the devices which effect the horizontal movements of the duct. This is done to enable the operator to stop the duct temporarily and deliver to some one part of the stack a larger quantity of straw. When this is done with the mechanism herein shown, I can still adjust the deflector by hand to deliver the straw at the desired points, and by so arranging the parts that the cord shall have one of its ends or fixed parts accessible to one standing on the ground in the way illustrated every desired adjustment of the parts of the duct, as the movements of the hood or deflector and the adjustment of the telescoping parts, can be accomplished from the ground and without requiring any climbing on the machine.

By having that part of the cord which is secured to the relatively stationary holder adjustable in the way illustrated—that is to say, constructing and arranging the parts so that more or less of the cord can be taken up or let out—the deflector can be governed as to the part which it shall follow of its total possible path. Thus if it be desired to have it move only in the lower part of its possible path the cord is lengthened or let out, but if it is desired to have it move only in the upper part of its path the cord will be shortened or taken in at the fastener H'. Thus provision is made for directing the straw at times mainly inward or toward the machine and then for directing it during a desired period mainly in a direction away from the machine.

Again, by having the other fastened part of the cord arranged to be adjusted along the vibrating lever K the throw of the deflector or the length of the arc through which it moves can be adjusted irrespective of the part of the path in which it may be held by the other part of the cord. Thus at the bottom portion of the stack it is preferable to have the power-transmitting cord secured farther away from the axis of the lever K, so that the vibrations of the latter will carry the deflector over a relatively long path and deliver the straw on a relatively wide base; but as the top of the stack is approached it can be narrowed or tapered by bringing the

end of the cord nearer to the axis, and then the movement of the deflector will be in shorter paths and the straw will be delivered over a reduced area, and by having both 5 these adjustments—namely, that which is attainable by having the cord adjustably attachable to the lever at different distances from the axis and that which is attainable by increasing or decreasing the total length of 10 the cord—I can provide for every desired result as to the delivery of the straw supplemental to what are provided for by having the duct itself extensible and vertically and horizontally adjustable, and, still further, it 15 will be seen that I not only have combined with the duct and the deflector movably mounted thereon the above-described means for effecting the movements of the deflector by hand and at will and also means for moving 20 the said deflector by power devices which do not require hand actuation, but also have arranged the devices which transmit motion to the deflector in such way that the duct can be lengthened or shortened without interference with or from such motion-transmitter. As shown, this is accomplished by 25 securing the cord at one point to the power devices and at another point to a relatively stationary holder and between said points 30 connecting it to the deflector by a cord-guide which permits the guide to move there-through while maintaining engagement, and I supplement these parts with a take-up for the cord, which supplies idle cord when necessary to permit extending the duct and takes 35 up such idle cord when the duct is shortened.

In another respect the present construction is a particularly advantageous one for embodying my invention—namely, in this, that 40 the power devices which actuate the deflector are situated at the axis around which the duct is vertically adjusted. When so situated, the distances between the driving and the driven parts can be maintained substantially 45 uniform irrespective of the horizontal or vertical position of the duct. Of course in this respect there can be variation and the power devices can be situated otherwise; but for some reasons I prefer that shown and 50 here referred to.

In Figs. 4 and 5 I have illustrated a slightly modified construction. In this construction O designates a cylindrical or tubular rock-shaft mounted in bearings o o on the second 55 duct-section B', and O' designates a rock-shaft which is mounted in bearings o' o' on the outer section B², the inner end of this shaft O' fitting within the shaft O, so as to move longitudinally thereof, but connected 60 thereto to vibrate about its longitudinal axis therewith. At its outer end the shaft O' is provided with a crank-arm o², to the free end of which is connected a short chain-section o³, the lower end of which may be engaged 65 with either of a series of apertures d⁶, formed in a bar d⁷, secured to the deflector-section D². To the rock-shaft O, near the inner end there-

of, is connected a crank-arm O⁸, the free end of which is connected to one end of a link P, the other end of which is connected to the 70 sprocket N. It will be seen that as the sprocket N is rotated in the manner hereinbefore described the link P and crank O⁸ will cause the compound rock-shaft O O' to vibrate about its longitudinal axis, and the upward 75 movement of the crank O⁸ at the outer end of said shaft will act to raise the deflector-section D². As the revolution of the sprocket N brings the parts P O⁸ O into their original positions the weight of the section D will 80 cause it to move downwardly about its pivot at d.

Any suitable power devices may be provided for driving the pinion c. In the drawings I have illustrated, more or less conventionally, a train of gearing connecting said pinion with a band-wheel U, mounted on the 85 thresher A.

At V is indicated the casing of the fan or ejector, by which the straw-moving blast of 90 air is created, said casing communicating with the uptake-duct A'.

From the above description and the drawings it will be seen that as the stacker tube or trunk is rotated about the vertical axis of 95 the cylindrical base C the deflector at the outer end of such duct will be automatically vibrated about its pivot and the straw escaping from the section B² will be guided to points relatively nearer or farther from the outer 100 end of the duct on a line transverse to that of the horizontal movement of such end, so that the straw will be uniformly distributed over the entire top of the stack.

However, I do not herein claim the specific 105 matters incident to the construction shown in Figs. 4 and 5, having made these the subject of claims in another application filed by me—to wit, Serial No. 696,875, filed November 26, 1898—but herein call attention to the 110 construction illustrated in said figures and last above described, inasmuch as it shows the fact that many features of my invention can be readily embodied in numerous forms of mechanism.

115 What I claim is—

1. In a pneumatic straw-stacker, the combination with the straw-duct, and the deflector, movably mounted at the outer end of said duct, of the automatically-acting power 120 devices for moving the deflector, independently of hand actuation, substantially as set forth.

2. In a pneumatic stacker, the combination with a discharge trunk or duct, and means 125 for automatically vibrating said trunk horizontally, of a straw guide or deflector pivotally connected to the outer portion of the trunk for directing the course of material escaping therefrom, and means for automatically vibrating said deflector about its pivot as the trunk or duct moves horizontally, substantially as set forth.

3. In a pneumatic stacker, the combination

of a discharge trunk or duct, means for vibrating said trunk horizontally, a deflector pivotally connected to said trunk and adapted to guide material escaping through the discharge-opening of the trunk, power devices for positively vibrating said deflector in one direction as the trunk moves horizontally, and a spring connected with the deflector for vibrating the same in the opposite direction, substantially as set forth.

4. In a pneumatic stacker, the combination of a discharge trunk or duct, means for vibrating said trunk or duct horizontally, a deflector pivotally connected to the outer end of the trunk, a stationary toothed segment extending concentric with the axis about which the trunk vibrates horizontally, and power devices movable with the trunk and engaging with said segment, for positively and automatically vibrating the deflector relatively to the trunk or duct as the latter is moving horizontally, substantially as set forth.

5. In a pneumatic stacker, the combination of a discharge trunk or duct, means for vibrating said trunk or duct horizontally, a deflector pivotally connected to the outer end of the trunk, a lever, K, movable with the trunk and having one arm connected with the deflector, a stationary toothed segment extending concentric with the axis about which the trunk vibrates horizontally, a wheel, N, gearing connected with said wheel and engaging with the stationary rack, whereby the wheel, N, will be rotated as the discharge-trunk moves horizontally, and a rod or link connecting said wheel, N, with the lever K, whereby the deflector will be automatically vibrated as the trunk moves horizontally, substantially as set forth.

6. In a pneumatic stacker, the combination of a discharge-trunk, means for positively vibrating said trunk horizontally, a wheel, N, moving with and adapted to be continuously rotated as the stacker-tube moves horizontally, and connections between said wheel and the deflector for positively rocking the latter about its pivot, substantially as set forth.

50 7. In a pneumatic stacker, the combination of a discharge trunk or duct, means for vibrating said trunk or duct horizontally, a deflector pivotally connected to the trunk for guiding material escaping therefrom, and means for automatically lifting said deflector out of the path of material escaping from the trunk, as the latter is moving horizontally, substantially as set forth.

60 8. In a pneumatic stacker, the combination of a horizontally-vibratable discharge trunk or duct, a deflector carried by the trunk or duct and normally extending into the path of material escaping therefrom, and means for automatically moving said deflector into and out of the path of material escaping from the trunk, as the latter moves horizontally, substantially as set forth.

9. In a pneumatic stacker, the combination of a discharge trunk or duct, a deflector pivotally connected to the trunk, a lever fulcrumed on the trunk, and having one end connected with the deflector, and power devices, adapted to be actuated by the horizontal vibration of the trunk or duct, for rocking said lever about its fulcrum and thereby vibrating the deflector about its pivot, substantially as set forth.

10. In a pneumatic stacker, the combination of a discharge trunk or duct, means for vibrating said trunk or duct, horizontally, a deflector pivotally connected to the trunk or duct, a lever, K, carried by the trunk, a cord or cable connecting the lever with the deflector, a wheel, N, movable with the trunk, a link pivotally connected to the face of said wheel and to said lever, a stationary toothed segment, extending concentric with the axis about which the stacker-tube vibrates horizontally, and power devices movable with the tube and connecting the wheel, N, with said stationary rack, substantially as set forth.

11. In a pneumatic stacker, the combination of a discharge trunk or duct, a deflector adjustably mounted on the trunk or duct, means for holding said deflector in either of several positions relative to the duct, means for automatically vibrating the duct and deflector horizontally, and means for vibrating the deflector relatively to the duct as the latter moves horizontally, substantially as set forth.

12. In a pneumatic stacker, the combination of a discharge trunk or duct, a deflector pivotally connected to the trunk or duct, a guide-sheave e carried by the deflector, a sheave G carried by the trunk or duct, a sheave G' arranged between said sheaves e, G, a rope or cable extending around said sheaves, power devices connected with one end of said rope or cable for positively moving the deflector about its pivot, and means for securing the other end of said rope or cable in any of several positions, to vary the normal position of the deflector relative to the deflector or duct, substantially as set forth.

13. In a pneumatic stacker, the combination of a discharge trunk or duct, a deflector adjustably supported on said trunk and adapted to project into the path of and direct the course of material escaping from the trunk or duct, and means for automatically moving said deflector vertically into and from said path, substantially as set forth.

14. In a pneumatic stacker, the combination of a discharge trunk or duct, a deflector adjustably supported on said trunk and adapted to move transversely of the planes of said trunk beyond the outer end thereof and to guide or direct material escaping from the trunk, means for moving said trunk and deflector about a vertical axis, and means for automatically moving the deflector into and from the path of material escaping from the trunk as the latter is vibrated horizontally, substantially as set forth.

15. In a pneumatic stacker, the combination of a discharge trunk or duct, a deflector or hood pivotally mounted on the trunk and adapted to project across more or less of the discharge end of the trunk or duct, means for positively vibrating the trunk or duct horizontally, and means for automatically vibrating the deflector relatively to the trunk or duct while moving therewith, substantially as set forth.

16. The combination of the straw-duct, the deflector movably mounted at the end of said duct, the automatically-acting power devices for moving the said deflector relatively to the duct, and hand operating means for imparting movements to the deflector supplemental to those imparted by the automatically-acting devices, substantially as set forth.

17. The combination of the straw-duct adapted to be adjusted vertically, the deflector movably mounted at the outer end of said duct, and the power devices for moving the deflector, mounted at the axis of adjustment of the duct, substantially as set forth.

18. The combination of the straw-duct movable horizontally and vertically, the power devices for moving it horizontally, the deflector movably mounted at the outer end of the duct, the deflector-actuating devices movable horizontally with the duct but immovable vertically and connected to, and operated by said power devices, substantially as set forth.

19. The combination of the straw-duct, the deflector movably mounted at the end of said duct, the rotating automatically-acting power devices, a vibrating lever, and a power-transmitter adjustably connected at either of several points along said lever, said lever and power-transmitter being interposed between the rotary power devices and the deflector for imparting motion to the latter, substantially as set forth.

20. The combination of the straw-duct, the deflector movably mounted at the end of said duct, the rotating automatically-acting power devices, a vibrating lever and a power-transmitter adjustable toward and from the axis of said lever, said power-transmitter and lever being interposed between the deflector and the rotary power devices for imparting motion to the deflector, substantially as set forth.

21. The combination, with the horizontally and vertically movable straw-duct, and the deflector movably mounted at the outer end of said duct, of the deflector-moving shaft mounted at the axis around which the duct moves vertically, means for rotating said shaft, and means interposed between said shaft and deflector for moving the latter, substantially as set forth.

22. The combination, of the vertically and horizontally movable straw-duct, the deflector

movably supported at the outer end of the 65 said duct, the automatic power devices for moving the deflector relatively to the duct, and the cord connected at one point to the said power devices, connected at another point to a relatively-fixed support, and at 70 points intermediate thereof connected to the deflector, substantially as set forth.

23. The combination, with the longitudinally-adjustable straw-duct, and the deflector movably mounted at the outer end of the 75 duct, of the automatically-acting mechanism for moving the deflector, the cord connected at one point to said power devices, and connected at another point to a relatively stationary holder, and between said points engaging loosely with a guide on the deflector, a cord-guide on the longitudinally-adjustable duct and a cord-guide which is relatively stationary, substantially as set forth.

24. The combination of the horizontally 85 and vertically moving straw-duct, the deflector movably supported at the outer end of the said duct, the automatically-acting power devices for moving the said deflector, the cord-guide on the deflector, the cord secured at one 90 point to said power devices and secured at another point to a relatively stationary holder, and at intermediate points engaging with the said cord-guide on the deflector and adapted to slip or move through said guide when it is 95 imparting motion to said deflector, substantially as described.

25. The combination, with the straw-duct, of the deflector movably supported at the outer end of the duct, the automatically-act- 100 ing power devices for moving the deflector, the pulley on the deflector, the cord engaging with and movable around the said pulley and connected at one point with the said power devices, and connected at another point to a 105 relatively stationary cord-holder situated near the ground whereby the deflector can be moved relatively to the duct either by hand or by said automatically-acting devices, sub- 110 stantially as set forth.

26. The combination, with the straw-duct, and the deflector movably mounted at the end thereof, of the automatically-acting power devices for moving the deflector relatively to the duct, a power-transmitter interposed between the deflector and said power devices and adjustable relatively thereto, substan- 115 tially as set forth, whereby the deflector will be automatically moved at one time through one path, and automatically moved at another 120 time through another path relatively to the duct, substantially as set forth.

In testimony whereof I affix my signature in presence of two witnesses.

JOHN B. BARTHOLOMEW.
